J. E. OSTLINE

DISCRIMINATING SIGNALING APPARATUS

Filed May 14, 1923

UNITED STATES PATENT OFFICE.

JOHN E. OSTLINE, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

DISCRIMINATING SIGNALING APPARATUS.

Application filed May 14, 1923. Serial No. 632,732.

This invention relates in general to discriminating signaling apparatus for automatic telephone systems, in which local subscribers call the special service operators for the purpose of initiating long distance, toll, or suburban calls. More specifically, the object of the invention is to provide a restricted service attachment at the substation, when special (long distance, toll, or suburban) service is denied, and means operative at the central office for automatically advising the special service operator of the character of the calling substation.

To accomplish the foregoing and other useful ends this invention comprises means which will be fully described in the specification which is to follow, reference being had to the accompanying drawing, which shows diagrammatically the apparatus and circuits involved in a complete connection between a calling subscriber at substation A and a trunk line extending to a special service operator's position M, by way of line switch C, selector E and repeater R.

The substation may be of any approved induction coil automatic type. As represented herein, it comprises essentially the receiver 1, switchhook 2, calling device 3, transmitter 5, induction coil 6, restricted service attachment S, condenser 9, and bells 10.

The restricted service attachment S comprises essentially the following: spring 40, to which is fastened the iron member 8, and which has a contact point in its end; spring 7 which has a contact point in its end; and supporting member or bracket 41 which may be mounted on the terminal block in the bell box, as in this case, or other convenient points so long as operation of the attachment is permitted. Springs 40 and 7 and supporting member 41 are assembled by means of various washers, insulators and screws 43. Adjusting screw 42, in supporting member 41, is used to secure the proper tension in spring 40 thus permitting it to operate only under certain conditions.

The line conductors 11 and 12 of the substation A are connected at the central office to the individual line switch C which is mechanically of the rotary type in which the

wipers have no normal position and move in a forward direction only.

Line switch C has access to a plurality of trunk lines extending to selector switches, one of which is shown in outline at E, which are mechanically of the well known vertical and rotary type in which the bank contacts are arranged in horizontal rows or levels.

A selector switch of the foregoing description may be operated in response to the first digit in a called number to select one of the main groups into which the subscribers' lines in the system are divided. For this purpose the selector E, in common with other selectors may be given access to a number of groups of trunk lines (not shown), each of which groups extends to a group of second selector switches.

It is customary to use only nine of the first selector levels for trunking to second selectors, as outlined above, one of the levels, usually the tenth, being reserved for the trunks extending to the special service operators by way of repeaters such as the outgoing special service repeater R. One of these latter trunk lines, indicated in the drawing by the reference characters 97, 98 and 99, extends from bank contacts 65, 66 and 67 to the trunk apparatus associated therewith at the repeater R and thence by conductors 211 and 212 to the operator's position M.

The outgoing special service repeater R consists essentially of a plurality of relays, an individual signal lamp L, and an impedance coil 107, together with suitable circuits for performing the necessary functions, as will be pointed out. Battery B is preferably common to a group of repeaters such as R.

The terminating equipment at the special service operator's position consists essentially of the polarized relay 201, different colored signal lamps L¹ and L², and a key K. An operator's simple and well known head set circuit is also shown diagrammatically at O.

Having given a brief description of the apparatus, the operation of same will now be explained more in detail. For this purpose it will be assumed that the subscriber

at substation A, which subscriber it will be further assumed is to be denied special (toll) service, desires to call a special service (recording) operator O in order to place a long distance, toll, or suburban call, as the case may be. In order to do this, the subscriber at substation A removes his receiver and then dials the operator's number.

When the receiver is removed at substation A, line relay 14 energizes over line conductors 11 and 12, but the primary winding of the induction coil at the substation, in series with the line relay, is not energized sufficiently to attract armature 8. Upon energizing, line relay 14 places ground on private normal conductor 30 at armature 19, thereby making the calling line busy, and closing a circuit for switching relay 13 and stepping magnet 15 in series. As a further result of the energization of line relay 14, it connects test wiper 22 to the junction of switching relay 13 and stepping magnet 15 at armature 20.

In case the trunk upon which the wipers of the line switch are standing is idle, switching relay 13 energizes immediately. Assuming the trunk to be busy, however, switching relay 13 is short circuited by ground encountered on the busy test contact by test wiper 22 and does not energize, and the wipers are rotated step by step by the buzzer-like action of stepping magnet 15, which operates through test wiper 22. When an idle trunk is reached, which trunk it will be assumed is the one terminating in bank contacts 24, 25, and 26, switching relay 13, being no longer short circuited, energizes in series with stepping magnet 15. Stepping magnet 15, however, does not energize at this time on account of the high resistance of switching relay 13. Switching relay 13, upon energizing, opens a point in the test circuit and prepares the holding circuit at armature 17, and at armatures 16 and 18 disconnects line conductors 11 and 12 from the winding of line relay 14 and ground, and extends them by way of wipers 21 and 23, bank contacts 24 and 26, and the associated line conductors to the windings of the line relay of the selector E. The line and release relays (not shown) of the selector E now energize and prepare the switch for operation in the usual well known manner.

When the calling subscriber A operates his calling device in accordance with the special service (recording) operator's number, in this case naught (0), the selector E raises its wipers 62, 63 and 64 opposite the desired level, in this case the tenth, of bank contacts and then selects an idle trunk. It will be assumed that the trunk selected at this time is the one extending to outgoing special service repeater R, indicated as 97, 98 and 99. That being the case, line relays

101 and 104 of the repeater R energize over the calling line, the former closing a circuit at armature 114 for relay 103 by way of armature 118 and its resting contact, and at armatures 111 and 112 preparing a circuit over which battery B is subsequently connected in series with the exchange battery. Battery B is short circuited through the individual trunk lamp L for the time being, however, at armatures 116 and 121. Relay 103, upon energizing, places ground on release trunk conductor 98 at armature 120, thereby closing the usual holding circuit for the preceding switches E and C; opens one point in the short circuit of battery B at armature 121; and closes a circuit at armature 122 for relay 102 by way of ground, working contact of armature 113 and said armature. Relay 102, upon energizing, locks itself up at armature 117 by way of ground, working contact of armature 113 and said armature; places additional ground on release trunk conductor 98 at armature 115; opens at armature 118 the circuit for relay 103; and opens at armature 116 the short circuit of battery B. Pending the deenergization of relay 103, then, battery B is connected in the line circuit in series with the exchange battery over the following path: ground, relay 104, trunk line conductor 99, bank contact 67, wiper 64, bank contact 26, wiper 23, working contact of armature 18 and said armature, line conductor 11, calling device 3 (substation A), spring 4, transmitter 5, winding of induction coil 6, line conductor 12, armature 16 and its working contact, wiper 21, bank contact 24, wiper 62, bank contact 65, trunk line conductor 97, armature 125 and its resting contact, armature 111 and its working contact, signal lamp L, battery B, working contact of armature 112 and said armature, armature 126 and its resting contact, and relay 101 to grounded battery. These batteries in series energize the induction coil 6 (substation A) sufficiently to operate armature 8 of the restricted service attachment, which armature, as before mentioned, is tensioned against operating on the normal operating current. Armature 8 places ground on the line circuit by way of the working contact of spring 7 and shorts out relay 104 (repeater R).

Relay 104, upon deenergizing, closes a circuit at armature 124 for relay 106 as follows: ground, working contact of armature 114 and said armature, armature 118 and its working contact, armature 123 and its working contact (relay 103 being slow acting holds up sufficiently long to complete this circuit), armature 124 and its resting contact, relay 106 to grounded battery. Relay 106, upon energizing, locks itself up at armature 130 by way of ground, working contact

of armature 119 and said armature; and reverses the direction of signaling current to be applied to the selected trunk line, at armatures 129 and 131. Relay 103, upon finally deenergizing, again closes at armature 121 the local short circuit of battery B, and closes a circuit at armature 123 for relay 105 by way of ground, working contact of armature 114 and said armature, armature 118 and its working contact. The short circuiting of battery B, referred to above, allows armature 8 of the restricted service attachment at the calling substation A to fall back, thus removing the ground or short from the line circuit and allowing line relay 104 to reenergize.

Relay 105, upon energizing, opens at armatures 125 and 126 both sides of the test battery B circuit; and closes at armatures 127 and 128 the signaling current circuit as follows: ground, right hand winding of impedance coil 107, working contact of armature 131 and said armature, working contact of armature 128 and said armature, trunk conductor 212, polarized relay 201, trunk conductor 211, armature 127 and its working contact, armature 129 and its working contact, left hand winding of impedance coil 107 to grounded battery. Polarized relay 201 energizes over the circuit referred to above, and actuates its armature 203 in the proper direction to close a circuit for red lamp L² by way of key K. Red lamp L², upon lighting, notifies the operator of the call and that the substation is a restricted service (no toll) substation.

At an unrestricted substation no attachment is used, consequently when such a substation makes a call no ground will be picked up at an armature such as 8 to short out line relay 104 and close a circuit for relay 106. Signaling current will therefore be applied over the following circuit: ground, right hand winding of impedance coil 107, resting contact of armature 129 and said armature, working contact of armature 127 and said armature, trunk conductor 211, polarized relay 201, trunk conductor 212, armature 128 and its working contact, armature 131 and its resting contact, left hand winding of impedance coil 107 to grounded battery. Polarized relay 201, upon energizing, operates its armature 203 in the proper direction to close a circuit for white lamp L¹ by way of key K. White lamp L¹, upon lighting, notifies the operator of the call and that the substation is an unrestricted service substation.

Upon the operator receiving either the red or white signal, depending on the class of substation calling, she bridges her head set O across the trunk conductors 211 and 212 by means of key K thus permitting conversation between her and the calling subscriber and extinguishing the signal lamp. Upon learning the calling subscriber's desired

number or call, she either makes a ticket on the call or denies the service as the case may require in the usual well known manner.

Whatever may be the character of the conversation, the calling subscriber will finally terminate it and will replace his receiver, bringing about the disconnection of the apparatus in the usual manner. Briefly, upon the deenergization of the line relays 101 and 104, relay 102 deenergizes and breaks the holding circuit 98 at armature 115 whereby line switch C and the selector E are restored to normal position; and breaks the locking circuit at armature 119 for relay 106 in case same was operated. Relay 105 also deenergizes and disconnects the signaling current from the trunk circuit, whereupon all the apparatus will have been restored to normal.

Particular attention is directed to the fact that with the "attachment" applied at the substation it is possible to furnish restricted service to separate parties on party lines without interfering with the other subscribers on the line. The line extending to substation A, it will be understood, may be a party line, having one or more other stations connected in bridge thereof like substation A. It is also possible to restrict extension telephones or make them "no toll," which is of value to business houses where employees have access to said telephones.

Attention is further directed to the ease, simplicity and effectiveness of the scheme, as follows:

No change in circuits required at the substation.

No special changes or attachments to the line equipment is required in the central office.

No equipment, cabling or wiring required in the central office except at the outgoing special service repeaters, with a small direct current source.

No interference with transmission, nor inductance disturbances.

A positive visible restricted service (no toll) signal in front of the operator.

Having described my invention, what I consider to be new and desire to have protected by Letters Patent will be pointed out in the appended claims.

What I claim is:

1. In an automatic telephone exchange system, subscribers' lines whose stations are divided into two classes in accordance with the kind of service to which they are entitled, means for extending one of said lines to an operator's position, a switchhook and a calling device at the station on the calling line for controlling said means, a signal control device at the station on the calling line, and automatic means responsive to said control device when the subscriber calls for operating a distinctive signal before the operator to indicate to what class he belongs.

2. In a telephone system, a plurality of substations divided into classes in accordance with the kind of service to which they are entitled, the substations of one class being entitled to have calls charged, while the substations of the other class are not entitled to have calls charged, means for extending any line when calling to an operator's position, automatic means controlled from the substation on the calling line for informing the operator of the class to which the calling substation belongs, and devices provided only at the substations of the second class for controlling said automatic means.
3. In an automatic telephone system, a plurality of subscribers' lines, a plurality of subscribers' stations, certain of said stations having restricted service, a service restricting device at each restricted service station, means for extending any line to an operator's position, and means at the exchange operating differently depending on the presence or absence of a service restricting device at the substation on the calling line for giving the operator a characteristic signal without the knowledge of the calling subscriber when the calling station is a restricted service one.
4. In a telephone system, a plurality of subscribers' stations of different character, automatic switching equipment for enabling the subscriber at any station to extend a connection to an operator's position, and automatic means selectively controlled from the station on the calling line after said connection is completed for giving the operator a characteristic visible signal indicative of the character of the calling station without the knowledge of the calling subscriber.
5. In an automatic telephone system, a plurality of subscribers' stations having induction coil type telephones, certain of said stations having restricted service, an attachment on the induction coil at each restricted service station, automatic means enabling any subscriber to extend a connection to an operator's position, and means controlled by the attachment in case a restricted service subscriber is calling for causing a distinctive visible signal to appear at said operator's position to notify the operator of the class of station calling.
6. The combination, with restricted and unrestricted subscribers' stations, said restricted stations having an attachment placed on the induction coil, of a repeater, means whereby any subscriber can extend connection to said repeater and thence to an operator's position, means whereby said repeater tests for the presence of said attachment, and means whereby said attachment causes said repeater to reverse the direction of signaling current and give the operator a characteristic signal indicative of the class of station.
7. In a telephone system, party lines, a

plurality of stations on said lines divided into classes in accordance with the kind of service to which they are entitled, each party line having stations belonging to different classes, means for extending any line when calling to an operator's position, and automatic means for informing the operator of the class to which the calling station belongs.

8. In a telephone system, a line, a plurality of stations on said line divided into classes, each class comprising one or more of said stations, means controllable from any station on said line for extending the line to an operator's position, and automatic means for informing the operator of the class to which any calling station belongs.

9. In a telephone system, a line, a plurality of stations on said line, one of said stations being denied service of a particular kind, means controllable from any station on said line for extending the line to an operator's position, and means automatically responsive only in case the denied service station is calling for giving the operator a denied service signal.

10. In a telephone system, a line, two classes of stations on said line, means controllable from any station on said line for extending the line to an operator's position, two signals at the operator's position, and means automatically responsive in case a station of one class is calling for operating one of said signals and in case a station of the other class is calling for operating the other of said signals.

11. In a telephone system, a line, a plurality of stations on said line, one of said stations having a restricted service attachment placed on the induction coil, a repeater at the exchange having a line relay therein and a booster battery associated therewith, means whereby any subscriber can extend connection to said repeater and thence to an operator's position, a signaling circuit, means whereby said booster battery is connected temporarily in series with said line relay and with the exchange battery for energizing said coil to operate said attachment, means whereby said attachment shorts out said line relay, and means responsive to the deenergization of said line relay to cause a reversal in the direction of current in said circuit to give the operator a characteristic signal indicative of the class of station.

12. In a telephone system, a line, a plurality of stations on said line, one of said stations having a restricted service attachment placed on the induction coil, a repeater at the exchange having two line relays therein and a booster battery associated therewith, means whereby any subscriber can extend a connection to said repeater and thence to an operator's position, means for automatically causing one of said line relays to

connect said battery to said repeater for testing for the presence of said attachment, and means whereby said attachment causes the other line relay to be shorted out to give the operator a characteristic signal indicative of the class of station.

13. The combination, with restricted and unrestricted subscribers' stations, each of said restricted stations having an attachment placed on the induction coil, of a repeater having a line relay therein and a booster battery associated therewith, means whereby any subscriber can extend connection to said repeater and thence to an operator's position, means whereby said booster battery is temporarily connected in series with the exchange battery when said connection is extended to said repeater to test for one of said attachments, means whereby said attachment shorts out said line relay, and means responsive to the deenergization of said line relay to give the operator a distinctive class signal.

14. The combination, with restricted and unrestricted subscribers' stations, each of said restricted stations having an attachment placed on the induction coil, of a repeater, a polarized relay, means whereby any subscriber can extend connection to said repeater and thence to an operator's position, means whereby said repeater tests for the presence of one of said attachments, and means whereby said attachment causes said repeater to operate said relay to give the operator a characteristic signal indicative of the class of station.

15. In a telephone system, a line, a plurality of stations on said line, the restricted stations having restricted service attachments thereat, a repeater at the exchange, means whereby any subscriber can extend connection to said repeater and thence to an operator's position, an auxiliary battery associated with said repeater, circuit means for temporarily connecting said auxiliary battery in series with the exchange battery to test for the presence of one of said attachments, and automatic means in said repeater for causing a distinctive signal to be given to the operator, the particular type of signal depending upon whether an attachment is encountered at the substation or not.

16. In a telephone system, a line, a plurality of stations on said line, the restricted stations having restricted service attachments thereat, a repeater at the exchange, means whereby any subscriber can extend connection to said repeater and thence to an operator's position, an auxiliary battery associated with said repeater, circuit means for temporarily connecting said auxiliary battery in series with the exchange battery to test for the presence of one of said attachments, a current reversing relay in said repeater, a signaling circuit controlled

by said relay, and circuit means whereby said relay is operated only when an attachment is encountered to reverse the direction of current in said circuit to give the operator a characteristic signal.

17. In a telephone system, a plurality of subscribers' stations, a restricted service attachment at certain of said stations, means for extending any station to an operator's position, two signals at said position, means for operating one signal when there is no attachment at the calling station, and means for operating the other signal when there is an attachment at the calling station.

18. In a telephone system, a plurality of subscribers' stations of different character, automatic switching equipment for enabling the subscriber at any station to extend a connection to an operator's position over any one of a plurality of paths, and automatic means controlled from the station on the calling line and operated independent of the path over which the connection is extended for giving the operator a characteristic visible signal indicative of the character of the calling station without the knowledge of the calling subscriber.

19. In a common battery subscriber's telephone instrument, an electro-magnetically operated device responsive only to current different from the normal line current, a hook switch for connecting said device in the line circuit when the receiver is removed, and means controlled by said device for modifying the electrical condition of a line conductor.

20. In a common battery substation telephone instrument, an induction coil, and a contact device operated by said coil when the normal current flowing through its winding is increased.

21. In a common battery substation telephone instrument, an induction coil, a contact device operated by said coil when the normal current flowing through its winding is increased, and a circuit controlled by said device for grounding the line to which the instrument is connected.

22. In a telephone system, means for extending a calling line to an operator's position, an automatic device at the exchange operated responsive to the completion of said connection, a device at the calling substation controlled by said first device, and another device at the exchange controlled by said substation device to signal the operator.

23. In a telephone system, means for extending a calling line to an operator's position, a device at the exchange operable after the said connection is completed, a device at the calling substation controlled by said first device, and another device at the exchange controlled by said substation device to signal the operator.

24. In a telephone system, means for ex-

tending a calling line to an operator's position, an automatic device at the exchange operated responsive to the call, a device at the calling substation controlled by said first device, and another device at the exchange controlled by said substation device to signal the operator.

25. In a telephone system, means for extending a calling line, an automatic device at

the exchange operated responsive to the call, a device at the calling substation controlled by said first device, and a switching device at the exchange controlled by said substation device. 10

In witness whereof, I hereunto subscribe 15 my name this 9th day of May, A. D., 1923.

JOHN E. OSTLINE.
